UNITED STATES PATENT OFFICE

2,253,693

MUFFLER

Floyd E. Deremer, Detroit, Mich.

Application November 4, 1940, Serial No. 364,135

2 Claims. (Cl. 181—48)

This application relates to exhaust muffler or silencer constructions particularly useful with internal combustion engines.

The patent to Oldberg #1,975,861 of October 9, 1934, discloses an exhaust silencer in which there is a through flow tube, such as the tube 14 of Fig. 1, through which the sound waves and gases flow. The through flow tube 14 there shown is provided with numerous small perforations 19 opening into the surrounding chamber R. The tube 14 of that muffler is representative of those called "through flow."

It is to mufflers having tubes of that type, namely, the through flow type, that the invention hereof relates.

The principal object of the present invention is to provide a convenient and inexpensive silencing aid to be applied to a through flow tube of a muffler.

For an illustration of an embodiment of the invention, reference should be had to the appended drawing. In this drawing—

Fig. 1 shows a through flow tube of a silencer, to which is applied a silencing means of the invention;

Fig. 2 is a diagrammatic cross-section view on line 2—2 of Fig. 1;

Fig. 3 is a diagrammatic longitudinal view, corresponding to Fig. 1, and showing the use of a restrictor in the through flow tube;

Fig. 4 shows the part to be applied to a through flow tube.

Referring to the drawing, it will be seen that Fig. 1 shows, for use as part of a muffler, as for example, as the through flow tube 14 of the muffler of Fig. 1 of the Oldberg Patent #1,975,861, a tube 10 having numerous perforations 11. With such a tube, there may be utilized the part 15 which is in the form of a U shaped trough having its end open. The longitudinal edges 16 of the trough may be secured to opposite sides of the tube to provide a tunnel 17 (Fig. 3) along-

side the tube. Perforations 11 open into such tunnel at opposite ends thereof so as to provide communications.

The trough 15 is a convenient and inexpensive device for aiding in silencing. It has been found particularly useful where the through flow tube is itself formed with a restrictor, such as is shown at 20 in Fig. 3 hereof, as well as in a patent to Deremer No. 2,139,151, of December 6, 1938, where the through flow tube 14 thereof is indicated as having a restrictor 20, as well as numerous perforations in advance of as well as behind the restrictor.

The means hereof has been utilized successfully on various types of mufflers. One type upon which it has been used, shown in the patent to Oldberg #1,950,455, is known as the multiple pass silencer. In this embodiment, troughs 15 were utilized on the inner tubes 17 and 18 of the inlet and return passages.

Now having described the means herein disclosed, reference should be had to the claims which follow for a determination of the invention.

25 I claim:

1. In an exhaust silencer for internal combustion engines, a through flow tube, and a U shaped trough having its ends open, and its longitudinal edges secured to opposite sides of the tube to provide a tunnel alongside the tube, the tube having perforations opening to opposite ends of the tunnel.

35 2. In an exhaust silencer for internal combustion engines, a through flow tube, and a U shaped trough having its ends open, and its longitudinal edges secured to opposite sides of the tube to provide a tunnel alongside the tube, the tube having perforations opening to opposite ends of the tunnel, the tube having a restrictor between 40 said perforations.

FLOYD E. DEREMER.
